PAPER BOX

Clarence Lloyd Claff, Randolph, Mass.

Application May 11, 1935, Serial No. 21,022

5 Claims. (Cl. 229—34)

This invention relates to paper boxes and to a new and improved method of producing the same, one of the objects being to provide a box or cover which is strong and durable although made from stock much thinner than that commonly employed in the manufacture of boxes.

It is a further object of the invention to provide a paper box the exposed raw edges of which are so thin as to be practically unnoticeable so as not to present an objectionable appearance.

A still further object is to provide a laminated box formed of two webs of box board thinner than that commonly employed but which, when joined by an interposed layer of adhesive, provide a stronger structure than one made of a single thickness of thicker box board.

A still further object is to provide a box having a novel arrangement of interfitting or interlocking portions at the corners for preventing the end of the box from being torn out easily when subjected to pulling strains.

With the foregoing and other objects in view the invention resides in certain novel details of construction and combinations of parts and in certain new and novel methods of making a box which will be hereinafter more fully described and pointed out in the claims, it being understood that changes may be made therein within the scope of the invention as claimed.

In the accompanying drawings the preferred forms of the invention have been shown.

In said drawings

Figure 1 is a plan view of one end portion of the outer blank from which a box or box lid is to be formed.

Figure 2 is a top plan view of the inner blank thereof, the same being shown partly edged with reinforcing or kraft tape.

Figure 3 is a plan view shown one end portion of the two blanks superimposed.

Figure 4 is a bottom plan view of the parts shown in Figure 3, a portion of the outer blank being broken away to show the adhesive coating on the bottom of the inner blank.

Figure 5 is a perspective view of one corner portion of a partly completed box utilizing the assembled blanks shown in Figures 3 and 4.

Figure 6 is a vertical section through the end portion of the box showing the positions of the parts following the step succeeding that shown in Figure 5.

Figure 7 is a horizontal section through one corner portion of the completed box.

Figure 8 is a section on line 8—8 Figure 7.

Figure 9 is a section on line 9—9 Figure 7 and

showing the line 7—7 on which Figure 7 is taken.

Figure 10 is a top plan view of one end portion of the outer blank of a modified structure.

Figure 11 is a top plan view of one end portion of the inner blank of said structure.

Figure 12 is a perspective view showing the said end portions assembled and partly folded in the formation of a modified form of box.

Figure 13 is a horizontal section through one corner portion of the box made from the blanks 10 shown in Figures 10 and 11.

Figure 14 is a top plan view of one end portion of an outer blank used in the formation of another modified construction.

Figure 15 is a top plan view of one end portion 15 of the inner blank of said modified structure.

Figure 16 is a perspective view of said blanks assembled and partly folded in the formation of the box.

Figure 17 is a horizontal section through one corner portion of a completed box in which are used the blanks used in Figures 14 to 16 inclusive.

The two blanks used in the formation of this box are adapted to be cut from separate webs 25 of thin box board material, these webs being supplied from rolls and being brought together by any suitable mechanism. While the webs are being fed toward each other the outer surface of one web A will have applied to it a coating of paper 1 the side portions of which are folded over and affixed to the side edges of the web so as to produce a finished edge. As the other web B is advanced, its side edges are provided with lengths of kraft tape 2 which straddle and are affixed 30 to said edges for reinforcing purposes as shown in Figure 2. A coating 3 of adhesive is applied to the inner surface of the web A and another coating of adhesive 4 is applied to the outer surface of the other web B so that when these 35 webs are brought together the two coatings of adhesive will come together and produce a laminated web formed of two thicknesses of thin paper board and interposed thicknesses of adhesive.

In the structure illustrated in Figures 1 to 9 45 inclusive the webs are creased and cut before they are assembled so as to produce blanks of the proper shapes for forming the box to be made. The web A, for example, is creased longitudinally and transversely along lines indicated at 5, 6 and 50 7 respectively so as to divide side walls 8 from the main body portion 9 of the blank, and to divide end folds 10 from the body portion 9. As only one end portion of the blank has been shown in Figure 1 it is to be understood that the opposite 55

end portion is to be a duplicate of that which has been illustrated. Each end fold 10 is adapted to be bent along the crease 7 extending longitudinally thereof. Each crease 6 extends across the creases 5 so as to divide the side walls 8 of the blank from end flaps 11 each of which is of a length equal to the length of fold 10. Each flap 11 is reduced in width along a curved edge 12 merging into a straight edge 13 so that a clearance 14 is thus produced between the flap and the adjacent side of the fold 10, the inner end of this clearance being tapered due to the curvature of the edge at 12.

The other web B is also divided into blanks which are of the same length as those cut from the web A. The two ends of each blank formed from web B are duplicates but in the drawings only one of these ends has been shown. Each blank is provided with longitudinal creases 15 dividing the body portion 16 of the blank from the side walls 17. Each blank is also provided with transverse creases 18 each of which divides the body portion 16 from an end fold 19. This crease 18 extends across the creases 16 so as to divide the end walls 17 from flaps 20 each of which is of a length equal to the length of fold 19.

Each fold 19 has recesses 21 extending toward each other from opposite sides, the area of each of these recesses being substantially the same in size and area as the flap 11. The outer end portions of each fold 19 are spaced from the flaps 20 so as to leave clearances 22. In other words the outer portion of the fold 19 is shorter than that portion extending along the crease 18. This outer portion of the fold, which extends between the recesses 21 and the end of the blank, is divided from the remainder of the outer fold by a transverse crease 23 along which the fold is adapted to be bent as hereinafter explained.

It is to be understood that the distance between the creases 15 is substantially equal to the distance between the creases 5 and that the width of each reinforced wall 17 is substantially equal to the distance between a crease 5 and the edge of the paper 1. Thus when two blanks shaped as herein described are brought together and placed in superposed relation as in Figure 1 the fold 19 will be affixed to the fold 10 and the flaps 20 will be affixed to the flaps 11 all of which has been clearly illustrated in Figure 3. The paper covered edges of the walls 8 and flaps 11 will be folded over the reinforced edges of the side walls 17 and flaps 20 after the two blanks have been joined so that the walls will thus be given well finished edges when the box is completed.

Following the joining of the two blanks the joined flaps are bent at right angles to the walls of the blanks and said walls are bent along the creases 5 and 15 into positions perpendicular to the body portions of the blanks. Thus the joined flaps will be brought into upstanding positions above the creases 6 and 18. Thereafter the joined flaps 10 and 19 are bent upwardly along the creases 6 and 18 so that the flaps 11 will be received within the recesses 21 and following this procedure the outer portions of the two flaps are folded inwardly along the creases 7 and 23 so that the glued surface adjacent the ends of the outer portion of flap 10 will become affixed to those exposed inner surfaces of the flaps 20 exposed beyond the ends of the fold 19.

If desired an adhesive coating can be placed on all exposed portions of fold 19 between the free edge thereof and the crease 23 although as

before stated the adhesive exposed beyond the ends of this fold will serve to hold the fold in its final position shown in Figures 7, 8 and 9.

It will be noted that when the blanks are shaped and joined as described the only raw edges exposed at the ends of the box are those formed by the single outer thickness of the thin fold 10, the side edges of which will be exposed between the creases 6 and 7. However as this material is quite thin the raw edges will be inconspicuous and not objectionable. The interfitting parts of the blanks due to the provision of the flaps 11 and the recesses 21 materially strengthen the finished box at the corner portions so that it will not be pulled apart readily when subjected to strains.

Instead of providing blanks having the interlocking feature produced by the recesses 21 and the flaps 11, the blanks can be made as shown in Figures 10 and 11 wherein the body portion 24 of 20 the outer blank is separated by longitudinal creases 25 from side walls 26. A transverse crease 27 separates the body portion from an end fold 28 adapted to be folded upon itself along a transverse crease 29. Crease 27 also crosses the creases 25 so as to divide the end walls 26 from short flaps 30.

The other blank of which this modified form of box is to be made includes a body portion 31 separated by side creases 32 from side walls 33. A transverse crease 34 separates the body portion 31 from an end fold 35 divided by a transverse crease 36. This end fold is of less width than the body portion 31 and terminates inwardly from the lines of the creases 32 so as to leave clearances 37 between the ends of the fold 35 and flaps 38 which extend from the side walls 33. These flaps 38 are divided from the walls 33 by transverse creases 39.

The blank shown in Figure 10 can be provided with a paper covering 40 such as heretofore indicated at 1 and the blank shown in Figure 11 can be reinforced at its edges with kraft tape 41 as described in connection with Figures 1 to 9 inclusive. One surface of each blank has a coating of adhesive 42, these adhesive coatings being adapted to come together when the two blanks are placed in superposed relation with the fold 35 resting on and centered upon the fold 28. After the two blanks have thus been assembled the flaps 38 and 30 are bent perpendicularly to their walls 33 and 26 respectively and said walls are then bent perpendicularly to the body portions of the blanks so that the joined flaps will upstand from the creases 34 and 27. Folds 28 and 35 are then bent over these flaps so as to straddle them and be affixed thereto.

It is to be understood of course that both ends of each blank are to be duplicates.

In this modified construction the only raw edges exposed at the outside of the completed box are the side edges of those portions of the folds 28 located between the creases 27 and 29. As the outer blank is of thin box board, the edges thus exposed will be barely noticeable and will not mar the appearance of the finished box.

Instead of providing flaps 30 which are relatively short and which enable the corner portions of the box to be materially reduced in thickness, the side walls 43 and 44 of the respective blanks can be provided with flaps 45 and 46 each of which is of the same length as the end folds 47 and 48. Folds 48 are of less width than the fold 47 so that after the blanks have been assembled and folded the only raw edges exposed will

be those formed by the sides of fold 47 between its creases 49 and 50. In this modified form of box the end wall is more bulky than in the form shown in Figures 10 to 13 inclusive but nevertheless the raw edges are still barely noticeable because of the thinness of the material due to the reduction in thickness of the end walls at the sides.

Importance is attached to the fact that in each of the structures described, except that shown in Figures 14 to 17 inclusive the outer surface of each end wall is flat from one exposed raw edge to the other. This is due entirely to the interfitting formation of the end folds 10 and 19 and the corner wings which are made up of the affixed flaps 11 and 20 in the structure shown in Figures 1 to 9 inclusive. In the structure shown in Figures 10 to 13 inclusive the flat outer surface is due to the stepped formation of the corner wings formed by the affixed flaps 30 and 38, these stepped wings interfitting with the folds 28 and 35, one layer of the fold 35 lying in the same plane with the flaps 30 while one thickness only of the fold 28 laps the flaps 30 as clearly shown in Figures 12 and 13. While the box herein described is illustrated and referred to as having a coating 1 of paper, it is to be understood that any suitable coating material can be used in lieu of paper.

30 The term "box" as herein used is intended to apply either to the body portion of a box or to a cover for a box.

What is claimed is:

1. A paper box comprising inner and outer layers of boxboard material affixed to form a laminated structure, a layer of coating material applied to the outer surface of the outer layer, each layer having side walls with end flaps, and also having end folds, the fold of the inner layer terminating at its sides inwardly from the sides of the folds of the outer blank layer and the coating material being coextensive in length and width with the folds of the outer layer, the corresponding flaps of the inner and outer layers being affixed to form corner wings, and said wings being extended toward each other, one flap of each wing being smaller than the other, said folds being astride and affixed to the wings, a portion of the fold of the inner layer being positioned in the same plane with the smaller flaps of the wings whereby portions of the raw side

edges of the fold of the outer layer and the coating material only are exposed outside the box.

2. A paper box comprising inner and outer layers of sheet material affixed to form a laminated structure, each layer having side walls with end flaps, and also having end folds, the fold of the inner layer terminating at its sides inwardly from the sides of the folds of the outer layer, the corresponding flaps of the two layers being affixed to form corner wings, and said wings being extended toward each other, one flap of each wing being narrower than the other to provide a clearance thereunder, said folds being astride and affixed to the wings, portions of the fold of the inner layer being recessed to receive the narrow flaps, thereby to lie in the same plane therewith, the raw edges of a portion of the fold of the outer layer only being exposed outside the box and said portion being affixed to and flat upon the interfitting portion of the narrow flaps and the fold of the inner layer.

3. A paper box formed of affixed layers of box board forming a laminated blank having stepped corner wings, and a fold formed by the end of the laminated blank, said fold straddling and affixed to the wings to substantially conceal the inner and outer surfaces thereof and being stepped at its sides to interfit the stepped wings whereby the raw side edges of one layer only of the blank are exposed outside the box.

4. A paper box formed of affixed layers of box board forming a laminated blank having stepped corner wings, and a fold formed by the end of the laminated blank, said fold straddling and affixed to the wings and being stepped at its sides to interfit the stepped wings whereby one layer of the fold is positioned in the same plane with one layer of each wing and the raw side edges of the other layer only of the fold are exposed outside the box.

5. A paper box formed of affixed layers of box board forming a laminated blank having corner wings, and a fold formed by the end of the laminated blank, said fold straddling and affixed to the wings and being stepped at its sides whereby one layer of the fold is interfitted with and positioned in the same plane with one layer of each wing and the raw side edges of the outer layer only of the fold are exposed outside the box.

CLARENCE LLOYD CLAFF.
